KEY CHAIN

John V. Cavalero, Bloomfield, N.J.

Application February 26, 1959, Serial No. 54,752

Term of patent 14 years

(Cl. D17—3)

Fig. 1.

Fig. 2.

Fig. 1 is a perspective view of a key chain embodying my new design; and

Fig. 2 is a similar view, taken from the other side thereof.

The essential features of the key chain reside in the particular shape of the outer leaf member of the clip, wherein one leg portion of the outer leaf member is formed with straight sides while the other leg portion of the clip member is formed with oppositely curved wings and pointed tips formed at the ends of said wings.

I claim:

The ornamental design for a key chain, as shown and described.
